REVOLVING DEVICE FOR PILGER MILLS

Heinrich Heetkamp, Duisburg, Germany

Application December 28, 1931, Serial No. 583,526
In Germany December 27, 1930

2 Claims. (Cl. 80—14)

(Granted under the provisions of sec. 14, act of
March 2, 1927; 357 O. G. 5)

The present invention relates to a rotating device for pilger rolling mills in which the blank is rotated in known manner while being moved forward by means of a twist bar operating in a twist casing.

For proper operation it is necessary that the blank during each forward feed movement should be rotated through a definite angle, normally an angle of 90°. In order positively to attain this rotation especially with different roll diameters—the roll diameter determining the travel of the blank during the feed movement—it has been usual up to the present to exchange the twist-bar and the corresponding nut through which it moves. It has furthermore been proposed to dispense with the twist-bar and to dispose the sliding head in a slide channel provided with twist grooves; on account of its complicated design this construction did not find favour in actual practice. It has furthermore been proposed to release the twist casing—secured against rotation during the feed movement—after the desired twist has been attained, so that it could thus rotate freely during the forward axial movement of the bar; the low efficiency and uncertainty in operation of the device in practice make it scarcely worthy of consideration.

According to the invention it is proposed to form the bar with a twist only over a determined length which will suffice to produce the rotation desired, the twist casing in which the twist-bar moves being so constructed that the surfaces of the bar engage only in line contact therein, whereby the axial movement of the bar through the casing is rendered possible.

The twist bar is advantageously guided in the casing by means of rollers located therein.

The accompanying diagrammatic drawing illustrates by way of example one construction of the device according to the invention.

Figure 1 is a pilger rolling mill showing the device in longitudinal section.

Figure 2 is a sectional side elevation of the twist bar casing, on an enlarged scale.

Figure 3 is a sectional front elevation corresponding to Figure 2 taken through the twist bar casing.

Figure 4 is a side elevation of the twist-bar, and

Figure 5 is a cross-sectional end elevation of the twist-bar showing the guide rollers in position.

In the drawing the pilger rolls are indicated by the reference numeral 1. The feeder com-

prises the cylinder 2, the piston 3 disposed therein and the piston rod 4. The piston rod 4 is coupled at 5 to the twist-bar 6 which passes through the twist-bar casing 7 and is connected to the sliding head 8. The sliding head 8 serves as a carrier for the mandrel 9. The blank on the mandrel is indicated by the reference numeral 10. The twist-bar casing 7 is mounted on bearings 11 (Figure 2) so as to be rotatable and is provided in known manner with a ratchet toothed periphery 12. A pawl 16 is mounted under spring pressure adjacent the casing 7 to engage with the teeth of the ratchet 12 to permit rotation of the casing in one direction only. The casing 7 is bored to a diameter corresponding to the length of a diagonal of the twist-bar 6. In the twist-bar casing 7 there are mounted rollers 13 (Figures 2 and 3) which are rotatable on pins 14 and serve for guiding the twist-bar 6 in its axial movements. It will be seen that these rollers 13 make contact with the surfaces of the bar 6 only along the lines 15.

The bar is according to the invention (see Figure 4) twisted only over a certain part of its length, that is to say, over the length marked "X" in Figure 4. The remaining part of the lengths, which is indicated by the reference "Y" in the drawing, and which is connected to the sliding head 8 having no twist. The length "X" is selected so as to give the bar 6 the desired twist on that section of the bar passing through the twist casing, this length being independent of the total feed distance moved forward by the bar with the sliding head 8. As will be seen with reference to Figure 4, the total feed distance moved forward consequently amounts to X plus Y. The lengths X and Y are so selected that the length "X" is adapted to the smallest feed movement.

The operation of the device is such that during the feed movement of the blank the length Y of the bar first passes through the twist casing 7. During this part of the movement no rotation is given to the bar; the bar is rotated only after the length X enters the casing.

I claim:—

1. A device for use in pilger rolling mills for rotating the work in its feed movement, comprising a spindle adapted for connection to the rear of the work, the said spindle being provided with guide surfaces extending in the direction of its length, the said guide surfaces being twisted helically for a portion of their length and being straight for the remainder of their length, means for advancing and retracting the spindle and the

work, a fixed bearing member, a casing rotatably mounted in the said bearing member and through which the spindle extends, rollers carried by the said casing and adapted to engage the guide surfaces of the spindle in a plane perpendicular to the axis of the spindle, ratchet teeth formed upon the periphery of the casing, and resilient restraining means carried by the bearing member for engaging the said teeth.

10 2. A device for use in pilger mills for rotating the work in its feed movement, comprising a spindle adapted for connection to the rear of the work, the said spindle being provided with guide surfaces extending in the direction of its

15 length, the said guide surfaces being twisted heli-

cally for a portion of their length and being straight for the remainder of their length, means for advancing and retracting the spindle and the work, a fixed bearing member, a casing rotatably mounted in the said bearing member and through which the spindle extends, guiding means carried by the said casing and adapted to engage the guide surfaces of the spindle in a plane perpendicular to the axis of the spindle, ratchet teeth formed upon the periphery of the casing, and resilient restraining means carried by the bearing member for engaging the said teeth.
